Attorney

UNITED STATES PATENT OFFICE

CLIFFORD B. BACKES, OF WALLINGFORD, CONNECTICUT, ASSIGNOR TO M. BACKES' SONS INCORPORATED, OF WALLINGFORD, CONNECTICUT, A CORPORATION OF CONNECTICUT

PISTOL CAP

Application filed December 23, 1930. Serial No. 504,387.

This invention relates to new and useful improvements in a pistol cap and has for its object, among other things, to provide such a cap with means whereby it will automatically lubricate the parts of the toy pistol engaged by it during its travel and also will lubricate the anvil against which it rests while receiving the hammer blow.

To these, and other ends, my invention consists in the pistol cap, constructed substantially as hereinafter described and particularly pointed out in the claims.

In the drawings, wherein like numerals of reference designate like parts in the several figures;

Figure 1 is a fragmentary side elevation of a toy pistol with the cap chamber in its open position and loaded with my improved pistol cap;

Figure 2 is a perspective view of my improved pistol cap; and

Figure 3 is an enlarged sectional view of a portion thereof, taken generally upon line 3—3 of Figure 2.

My improved pistol cap is particularly adapted for use with a pistol wherein the cap during its intermittent travel moves over a guiding face before presentation between the anvil and hammer of the pistol.

Caps of this type have heretofore been found objectionable because they did not readily move over the guiding face. This is due to the fact that the cap is dry as well as slightly irregular upon its face at and adjacent to the area where the spot or dot of powder is placed.

The difficulty is exaggerated when pressure is applied to the cap to move it, which also has a tendency to press the same against the guiding face.

For these, and other reasons, it is a common experience to have this type of cap adhere to the guiding face with a resulting jam and prevent the automatic feed of caps to the hammer.

Such a cap is pressed against the face of the anvil by the blow of the hammer and frequently adheres thereto. Successive presentation of caps to the anvil after the paper strip has adhered thereto causes an accumu-

lation of paper on the anvil which forms a resilient cushion and an imperfect action of the pistol.

These, and other objections to the present form of cap are eliminated in my improved cap, which is provided with a lubricant which is spread over the guiding face and the anvil during its travel through the pistol.

In the drawings I have only shown a single spot of such lubricant, but two or more spots thereof may be applied if desired.

In the drawings I have shown a strip of caps in roll form, designated 5, which is of the usual type, having a succession of powder spots 6 therein, which are spaced apart the required distance to accommodate the mechanical feed for successive presentations to the anvil. The lubricant 7 is placed in one area, or several areas, and in any desired form, upon that face of the strip that passes over the guiding face and is presented to the anvil.

This lubricant may be of any material that will adequately meet the requirements, paraffin being one of such materials.

The pistol illustrated in the drawings is one of the many forms of pistols with which my improved cap is usable. As shown, it has a barrel 8 and grip 9, which is hollow and provided with a post 10 over which the cap roll is placed.

Pivottally mounted in the grip and actuated by the manipulation of a trigger 16 is a hammer plate 11 terminating at one end in a hammer 15 and having a wall 12 with a guiding face 13 upon one side thereof, over which the cap strip passes before being presented in front of the anvil 14, as is usual.

The hammer plate 11 is controlled in its movement so that when the hammer moves away from the anvil, the end of a spring finger 17 which engages the cap strip, advances it so that the next succeeding spot or dot of powder is presented in front of the anvil. During this travel of the strip the lubricant 7 is applied to both the guiding face 13 and the anvil 14.

What I claim as new is:

1. A pistol cap composed of a strip of flexible material with one or more powder

spots thereon, and a lubricant upon said strip, said lubricant being placed adjacent to that end of the strip first presented to the hammer mechanism of the pistol.

5 2. In combination with a pistol having an anvil, a hammer and an intermittent feed; of a pistol cap composed of a relatively long strip of flexible material with one or more powder spots thereon, advanced between the
10 anvil and hammer by said intermittent feed, so as to successively present the powder spots in line with said anvil; and a lubricant upon that face of the strip opposite to the hammer, which during the passage of the strip
15 over the anvil lubricates the same and thereby minimizes an accumulation of the flexible material of the strip on the anvil through the pressure of the hammer.

20 3. In combination with a pistol having an anvil and a hammer; of a pistol cap that passes therebetween, said pistol cap being composed of a strip of flexible material with one or more spaced powder spots thereon with a lubricant upon the strip which lubricates the anvil and thereby minimizes an accumulation of the flexible material of the strip on said anvil through the pressure of
25 the hammer thereagainst.

30 4. In combination with a pistol having an anvil, a hammer and an intermittent feed; of a pistol cap composed of a relatively long strip of flexible material with one or more powder spots thereon, advanced between the anvil and hammer by said intermittent feed
35 and over a surface forming part of the feed mechanism, so as to successively present the powder spots in line with said anvil; and a lubricant upon that face of the strip opposite to the hammer, which during the passage
40 of the strip over the said feed surface and anvil lubricates the same and thereby facilitates the movement of the strip during the feed thereof and minimizes an accumulation of the flexible material of the strip on the
45 anvil through the pressure of the hammer.

5. A pistol cap composed of a strip of flexible material having one or more powder spots thereon, and a lubricant upon one side of the strip.

50 6. A pistol cap composed of a strip of flexible material having one or more powder spots thereon, and one or more spots of paraffin, as a lubricant, upon one side of the strip.

In testimony whereof, I have hereunto affixed my signature.

CLIFFORD B. BACKES.
